IMPULSE TRANSMITTING DEVICE

Joseph Léon Auguste Vanheerswyngels, Brussels,
BelgiumApplication May 9, 1933, Serial No. 670,137
In Belgium May 12, 1932

7 Claims. (Cl. 179—90)

My invention relates to improvements in electrical impulse transmitting devices such as those used in telephone systems of the type having an automatic central station, and more especially to that part of the apparatus adapted to transmit the called number to the central station of the system.

Heretofore, in mechanisms of this type, the number called was relayed to the central station by the displacement of one or more rotatable members. A rotatable disc or dial, one for each figure of the called number, is rotated an amount proportional to each of the figures of the numbers, and the impulse formed by each revolution transmitted to the central station while the disc returned to its initial position. The disadvantage of such systems resides in the fact that, during the successive operations required to dial a desired number, one making the call often becomes confused and forgets the remainder of the number being called, resulting both in a loss of time and the cost of making the call. It is an object of this invention to provide such a telephone system whereby this disadvantage is obviated.

Another object of my invention is to provide means whereby it is possible to dial a given number but once if the said number is to be called several times in succession.

A further object of the invention is to avoid the necessity of removing the receiver of the telephone apparatus while putting through the call for any desired number.

An impulse transmitting system embodying the features of this invention is illustrated in the accompanying drawings in which:

Fig. 1 is a plan view of an impulse transmitting device associated with a number forming member;

Fig. 2 is a side elevation of a modified form of a number forming member;

Fig. 3 is a plan view of an electric contact plate used in conjunction with the number forming member; and

Fig. 4 is a plan view of a number card.

The impulse transmitting device illustrated in Figure 1 of the drawings consists of a transmitting member A and its associated number forming member B. The member A is adapted for use in a telephone system wherein the numbers called are composed of three figures. The system may, however, be altered to accommodate numbers of more than three figures if desired.

The transmitting member A has as many groups of contacts as the number being called has figures. In the illustration shown, the de-

vice is provided with three groups of contacts P, S, and T. Each individual group is composed of twenty contacts arranged on the same circumference of the disc and forming a crown. In each group of twenty contacts there is a first series of ten contacts 1, 2, 3, . . . 0, corresponding to the figures 1, 2, 3, . . . 0. Between each contact of the first series of ten contacts there is a contact 11. Consequently, in each group P, S and T, there are nine contacts 11 forming a second series of contacts, and separating the groups P, S, and T there is a contact 12.

The contacts 11 of each group are connected together by a wire 13 which in turn is connected to both the contacts 12 and arranged on each side of the groups. One of the contacts 12, for instance the contact 12', is connected to one of the terminals 14—15 of the telephone system. The leads 16 and 17 are the terminals of the telephone line.

One of these terminals, the terminal 16, is connected to a fixed wiper 18 resting on a ring 19 surrounding the axis of a brush or commutating switch 20 resting normally on the contact 12'. This switch is adapted to be rotated about the axle 19'. Any well known type of governor mechanism may be used for controlling the speed of rotation of the wiper 18 if desired.

When the apparatus is not in use, the circuit through terminals 14 and 15 to the telephone apparatus is closed, the current from the central station passing from the terminal 16 to the wiper 18, the ring 19, brush 20, contact 12', terminal 14 (telephone apparatus which is not shown), terminal 15, terminal 17 and the telephone line connected to the latter. This position of the brush 20 corresponds to the position of rest of the transmitting member during when a call can be produced by another set and conversation between the two started.

From each of the first series of contacts 1, 2, 3, . . . 0 of each group runs an insulated conductor 21. The conductors 21 of each group are connected together by a cable 22. Each of the cables ends in an element of the number forming member B, which member comprises as many elements as there are groups of contacts in the transmitting device.

The number forming member B shown in Figure 2 of the drawings, comprises one group of fixed contacts 23 and one group of fixed contacts 24, each group being separated from each other and arranged one above the other. Each group forms three parallel rows of ten contacts, the number of rows in each group depending upon

the number of figures in the called number. The contacts 23 and 24 are connected in pairs by means of conductors 25 and 26 to a single conductor 21 forming part of a cable 22 composed of ten conductors 21 originating from a series of ten contacts 1, 2, 3, . . . 0 of the impulse transmitting device. Between the two groups of fixed contacts 23 and 24 there is arranged a plate 27 carried by supports 28 pivoted at 29 and oscillating on pins 30.

The plate 27 is provided with a metal blade 31 disposed on both the upper and lower sides of the plate. The blade 31, as shown in Figure 3, is provided, by means of a stamping operation, with small rectangular slips 32. These slips project slightly beyond the surface of the blade 31 and act as springs. Each slip is provided with a circular portion 33 at its free end adapted to exert a pressure on the corresponding fixed contacts 23 or 24 of each group, depending upon the movement of the plate 27. In the lowered position of the plate 27, the portions 33 will rest upon the contacts 24 and, as seen in the drawings, in the upper position of the plate 27, they will rest upon the contacts 23. The plate 27 is held in position by means of a spring 34 which is fixed to the casing of the apparatus at 35. The metal blades 31 of the plate 27 are connected by means of a conductor 36 to one of the contacts 12 between each of the groups P, S, and T and to the conductor connecting the terminal 15 of the telephone apparatus to the terminal 17 of the telephone line.

In the illustration shown in Figure 2, the group of fixed contacts 23 is used for the formation of all desired call numbers and the group of fixed contacts 24 for calling numbers which have been previously prepared.

The group of fixed contacts 23 corresponds in each line to one of the figures forming part of the number to be called and are connected by the conductors 21 of the cable 22 to the corresponding contacts 1, 2, 3, . . . 0 of one of the group of contacts P, S and T. The group of fixed contacts 24, by means of the conductors 28, is also connected to the corresponding contacts 1, 2, 3, . . . 0 of the group of contacts P, S, and T.

Corresponding to each line of contacts 23, there is a bar 37 of insulating material, provided at one end with a bevelled edge 38 and adapted to be displaced by a controlling knob 39 disposed at the other end. Each bar 37 carries, in agreement with the fixed contacts 23 and 24, the figures 1, 2, 3, . . . 0, and each of these figures can be brought, by displacement of the bar, under an opening 40 formed in the wall 41 of the casing of the apparatus above a fixed support 42 used as a guide for the movable bars 37.

The operation of the apparatus is as follows when it is desired to obtain a predetermined call number:

As has been explained heretofore, the impulse transmitting member A is at rest when the telephone apparatus is normally in circuit. If, at that instant, all the insulating bars 37 are completely pushed into the position as shown in Figure 2, and the movable plate 27 is in its upper position, all the fixed contacts 23 are insulated by means of these bars from the projections 33 carried by the slips 32 of the metallic blade 31 which is provided on the plate 27. If then, the brush 20 is caused to be rotated manually, for example, around the axle or pivot 19, it will, upon leaving the contact 12' connected to the terminal 14 of the telephone apparatus, put the latter out of circuit.

The switch 20 then passes successively over all the contacts of the groups P, S, and T and comes again to rest on the contact 12' from which it started; the current, coming from the terminal 16 of the telephone line and passing through the fixed wiper 18, the ring 19 and the switch 20, passes, each time the switch comes into contact with one of the contacts 11, through the conductor 13 connected to this contact and to two of the contacts 12 situated between the groups of contacts P, S, and T, to the conductor 36 through which it is returned to the central station through the conductor connecting the terminal 15 of the telephone apparatus to the terminal 17 of the line. Also, each time the switch 20 comes into contact with one of the contacts 1, 2, 3, . . . 0 the current is interrupted as these contacts are each connected by means of one of the conductors 21 to one corresponding contact of the groups of fixed contacts 23 which are insulated by the bars 37 from the contacts 33 of the movable plate 27, the passage of the current through the conductor 36 to the line being impossible. Consequently, if all the bars, three in number being illustrated, insulate all the contacts 23 from the contacts 33, the switch 20, during its movement on the contacts 1, 2, 3, . . . 0 of each group of contacts P, S, and T will produce for each group a ten impulse train, the impulses being in reality produced by current interruptions in the line going to the central station. In the illustration shown, the position of the bars 37 is such that the figure "000" is seen under the opening 40, this figure giving rise to ten successive impulses or interruptions.

On the other hand, a correspondence between 1, 2, 3, . . . 0 of the fixed contacts 23 and 1, 2, 3, . . . 0 of the contacts 33 of the slips 32 will reduce the number of impulses which are transmitted for each of the groups of contacts P, S, and T to nine, eight, seven, etc.

The contacts 23 which correspond in each line of contacts to the figures 1, 2, 3, . . . 0 of the bars 37 being connected by the conductors 25 to the contacts 1, 2, 3, . . . 0 of each of the groups P, S, and T of the impulse transmitting member A, it will be easily understood that in order to form any desired number, it is only necessary to have at one's disposal as many bars 37 as there are figures in the number to be formed and the number of contacts of the transmitting member comprising as many groups P, S, and T of contacts as there are bars 37.

In order to form the number desired, the movable bars 37 are displaced an amount so as to cause the number to be formed to appear under the opening 40. Each bar then cuts out of circuit as many contacts 23 and consequently as many contacts 1, 2, 3, . . . 0 of the corresponding groups P, S, and T, as there are units in the figure of each individual bar which appears under the opening 40.

The number forming member B can also be used for the calling of a number which has been previously prepared. For this purpose, a plate of insulating material, which will hereinafter be termed a number card, is used. Such a number card is illustrated in Figure 4, and it is used in combination with the group of contacts of the impulse transmitting member A in the same manner as the groups of contacts 23. This card is provided with columns of figures 1, 2, 3, etc., one column for each digit of the telephone number. By a stamping operation the numbers in each column

in excess of the figure of the telephone number represented by that column are punched or cut out. The card illustrated corresponds to the number 407, the perforations being represented by circles not provided with figures. A number card for such telephone numbers as are frequently called by the subscriber may be constructed in this manner for the convenience of the subscriber.

10 The number card is also provided with additional perforations 45 which serve as guides in the positioning of the card in the mechanism. They can also be provided with tab 46 so that they are easily available when kept in filing cabinets. Provision is also made, as at 47, for any indicia or advertising matter to be printed on the card.

In operation, the number card is placed, at the start of the formation of the called number to 20 which it corresponds, on the lower group of the fixed contacts 24, and the movable plate 27 is lowered on the card in such a manner that the contacts 33 of the metallic blade 31 on the lower face of the plate 27 close the circuits corresponding to the perforations 44 so that when the switch 20 is rotated the impulses correspond to each of the figures of the number to be called.

The apparatus may also be provided with a movable member suitably controlled that will 30 cause the switch 20 to be completely rotated at the desired moment and by a lever modify the position of the plate 27 and indicate this position with respect to the groups of fixed contacts 23 and 24.

35 The impulse transmitting member could also be provided with a lower number of groups of contacts 1, 2, 3, . . . 0, the switch 20, in such a case, making a greater number of revolutions in order to transmit a number. In such a case, an 40 automatic commutator of any well-known type could cooperate with the crown in order to obtain the interruption resulting from the passing of the switch over a group of contacts. If the number of contacts of the crown be only one, the 45 switch 20 will effect as many revolutions as the numbers of the telephone system comprise figures.

It will be obvious that various changes may be made by those skilled in the art in the details of the embodiments of the invention illustrated in 50 the drawings and described above within the principle and scope of the invention as expressed in the appended claims.

What I claim is:

1. An impulse device for an automatic telephone 55 system comprising means for causing a series of electrical impulses including a plurality of fixed contacts including two groups, each group including alternate contacts of a series of contacts, a movable contact mounted to engage the several 60 fixed contacts successively, and control means for modifying the number of impulses caused by the movement of the movable contacts over the fixed contacts including means for varying the electrical interconnection of the fixed contacts.

65 2. An impulse device for an automatic telephone system comprising means for causing a series of electrical impulses including a plurality of fixed contacts including two groups, each group including alternate contacts of a series of 70 contacts, a movable contact mounted to engage the several fixed contacts successively, and control means for modifying the number of impulses caused by the movement of the movable contact over the fixed contacts including another set of a 75 plurality of contacts comprising, one for each

contact in one of the series of contacts in the impulse causing means and each electrically connected to one of such contacts, and means cooperating with said last mentioned set of contacts for connecting the contacts of the control member to the contacts of the other group of contacts in the impulse causing means. 5

3. An impulse device for an automatic telephone system comprising means for causing a series of electrical impulses including two groups 10 of fixed contacts, each group including alternate contacts of a series and one group having nine contacts and the other ten contacts, a movable contact mounted to engage the fixed contacts successively, and control means for modifying 15 the number of impulses caused by moving the movable contact over the fixed contact including another set of ten fixed electrical contacts, each electrically connected to a contact of the group of ten contacts in the impulse forming means, 20 and means cooperating therewith for electrically connecting the contacts of the control means to the group of nine contacts in the impulse forming means.

4. An impulse device for an automatic telephone 25 system comprising means for causing a series of electrical impulses including two groups of fixed contacts, each group including alternate contacts of a series of contacts and one group having nine contacts and the other ten contacts, 30 a movable contact mounted to engage the fixed contacts successively, and control means for modifying the number of impulses caused by moving the movable contact over the fixed contact including another set of ten fixed electrical 35 contacts, each electrically connected to a contact of the group of ten contacts in the impulse forming means, means cooperating therewith for electrically connecting the contacts of the control means to the group of nine contacts in the 40 impulse forming means, and means for varying the number of contacts in the control means connected to the group of nine contacts in the impulse forming means.

5. An impulse device for an automatic telephone 45 system comprising means for causing a series of electrical impulses including two groups of fixed contacts, each group including alternate contacts of a series of contacts and one group having nine contacts and the other ten contacts, 50 a movable contact mounted to engage the fixed contacts successively, and control means for modifying the number of impulses caused by moving the movable contact over the fixed contact including another group of ten fixed electrical 55 contacts, each electrically connected to a contact of the group of ten contacts in the impulse forming means, means movable into cooperation with the contacts of the control means for electrically connecting the contacts of the control means to the group of nine contacts in the impulse causing means, and means for varying the number of contacts in the control means connected to the group of nine contacts in the impulse forming means upon operation of said movable means. 60 65

6. An impulse device for an automatic telephone 70 system comprising means for causing several series of electrical impulses including several series of fixed electrical contacts, one for each number in the call numbers of the telephone system and each series including two groups of alternate contacts, one group having ten contacts and the other group having nine contacts, a movable contact mounted to engage the fixed contacts successively, and control means 75

for modifying the number of impulses in each series of impulses caused by moving the movable contact over the fixed contacts including a control for each series of fixed contacts in the impulse forming means and each control comprising ten fixed electrical contacts, each connected to a contact of the group of ten contacts in the corresponding series of contacts in the impulse forming means, means movable into cooperation with the fixed contacts of the control means for electrically connecting the contacts thereof to the group of nine contacts in the corresponding series of contacts of the impulse forming means, and means for varying the number of contacts of the several controls connected to the group of nine contacts in the corresponding series of contacts of the impulse forming means upon operation of said movable means.

7. An impulse device for an automatic telephone system comprising means for causing several series of electrical impulses including several series of fixed electrical contacts, one for each number in the call numbers of the telephone system and each series including two groups of

alternate contacts, one group having ten contacts and the other group having nine contacts, a movable contact mounted to engage the fixed contacts successively, and control means for modifying the number of impulses in each series of impulses caused by moving the movable contact over the fixed contacts including a control for each series of fixed contacts in the impulse forming means and each control comprising ten fixed electrical contacts, each connected to a contact of the group of ten contacts in the corresponding series of contacts in the impulse forming means, means movable into cooperation with the fixed contacts of the control means for electrically connecting the contacts thereof to the group of nine contacts in the corresponding series of contacts of the impulse forming means, and means individual to each control for varying the number of contacts of the control connected to the group of nine contacts in its corresponding series of contacts of the impulse forming means upon operation of said movable means.

JOSEPH LÉON AUGUSTE
VANHEERSWYNGHELS.
